Application filed June 6, 1892. Serial No. 435,757. Term of patent 7 years.

To all whom it may concern:

Be it known that I, ROBERT H. The leading feature of my design for the casing of a coin-actuated vending-machine

consists in a box-shaped pedestal represented by the lower section B and an upper section A in the form of a mammoth cigar standing erect with its lighting end downward on the pedestal.

What I claim is—

The design herein shown and described for a casing of a coin-actuated vending-machine.
